FREDERICK COATES, OF NEW YORK, N. Y., ASSIGNOR TO STANDARD AUTOMATIC MACHINE COMPANY, OF ROCHESTER, NEW YORK, A CORPORATION OF NEW YORK.

LABELING-MACHINE.

1,088,208.

Specification of Letters Patent.

Patented Feb. 24, 1914.

Application filed October 20, 1911. Serial No. 655,704.

To all whom it may concern:

Be it known that I, FREDERICK COATES, a citizen of the United States of America, and resident of New York, in the county of New York and State of New York, have invented certain new and useful Improvements in Labeling-Machines, of which the following is a full, clear, and exact description.

10 This invention relates to a machine for automatically applying labels onto boxes, or other objects to be labeled, which labels may be applied on one side only, or on more than one, or around all sides of the box.

15 The invention as carried out for the fullest capability thereof resides in a machine comprising means for automatically delivering boxes, or other objects, to receivers or carriers which respectively take them individually and convey them subject to the action of gumming means, which means also imparts a surfacing of gum on the under side of a flat faced member or members adjacent and bodily movable in conjunction with each of the box carriers, such machine further comprising means for moving a label support with labels thereon, so that the uppermost one of the labels becomes adherent on the gummed surface of the box, and on the surface of the gum receiving member or members adjacent which the box is brought, the said machine moreover comprising a set, or duplicated sets, of label folding or wrapping mechanisms or intumers together with means for both expelling the boxes from the box carriers and for stripping the labels from adhesion on said gum surfaced members, and forcing the boxes with the labels into the folding mechanisms, so that the labels will be wrapped partially or entirely around the boxes, and stuck thereto.

20

35

40

An object of this invention is to produce a machine of extremely simple and inexpensive character; and the machine is, furthermore, by reason of the organization or combination and arrangement of the parts thereof, susceptible of being rendered a duplex machine whereby the labeling operations are simultaneously performed on two boxes, thus correspondingly increasing the operative capacity.

Other objects and advantages are attained in and by the organized mechanism, as will hereinafter be rendered apparent.

The invention is described in conjunction with the accompanying drawings and is set forth in the claims.

In the drawings:—Figure 1 is a plan view of the duplex box labeling machine with the upper feed table and pair of box guiding chutes omitted. Fig. 2 is a front elevation of the complete machine; Fig. 3 is a view showing the parts of the machine in horizontal section and partial plan view as seen at and below the plane indicated by line 3—3, Fig. 2. Fig. 4 is a vertical cross sectional view on line 4—4, Fig. 1. Fig. 5 is a sectional view through the gum box and its gum roll as taken on line 5—5, Fig. 1, showing in elevation a box carrier with a box therein and gum receiving members oppositely disposed in relation to the box carrier. Fig. 6 is a perspective view showing the construction of the lower portion of one of the box guiding chutes and its relation to a box carrier. Fig. 7 is a partial vertical sectional view on line 7—7, Fig. 1; and Fig. 8 is a sectional elevation through one of the folding mechanisms showing the position of parts in relation thereto at the time the plunger is forcing a box from the box carrier into the folding box.

Similar characters of reference indicate corresponding parts in all of the views.

In the drawings, A represents the main support or bed of the machine provided with uprights $a a$ at opposite sides of one end portion of such bed, formed with vertical ways a^2 for slides a^3 to be hereinafter referred to. Centrally between the slides is the circular and revoluble table-like support or dial B which marginally thereof is provided with a rectangularly spaced series of receivers and carriers C for the boxes which are fed thereto gravitatively by their guidance down the chutes D D. In the machine here represented, there are six of the box carriers C, four thereof being visible in Fig. 1 and two thereof at the front and rear of the machine being concealed by the plunger heads E E. Each box carrier C has substantially the form of a vertical trough or, otherwise described, that of a topless and bottomless box and from which its front vertical wall is absent; and each box carrier is supported outside of the margin of the intermittently revoluble support or dial B by the horizontal segmental bracket plates c which are screwed on the

top of, and edgewise overhang the revolute support B.

The guide chutes D D are arranged diametrically opposite each other in a line which is oblique to the front of the machine; and while representation thereof is omitted in Fig. 1 for avoidance of obscurity of other parts, it is understood that their lower delivery portions are directly over the box carriers C C at the points 10 and 12.

Each box carrier has provision so that a box delivered thereto from one of the chutes will be prevented from falling downwardly through the carrier, but will be yieldingly retained in the carrier with its bottom as low as, or very slightly lower than, the bottom of the carrier; and as most particularly shown in Fig. 7, the carrier has on one side thereof a retaining finger d through the upper extremity of which a retaining screw d¹ is loosely passed, while through an aperture in an intermediate part of the finger the shank of a headed screw d² is passed for penetration into the side wall of the box carrier. Between the head of the screw d² and the outer face of the finger is a spiral spring d³; and the lower extremity d⁴ of the finger is slightly inwardly turned to form a shoulder or retainer for intercepting the box when it has come fully to, or slightly below, the bottom of the box carrier.

There are, oppositely in relation to the box-carrier, a pair of bars or plates F F arranged in a line with each other which is perpendicular to a radial line from the center of the dial B, so that one travels in advance and the other directly at the rear of the box carrier as it has its step by step revolute movements. These bars F F are supported by the bracket plates e at their under sides and at the outer edge portions of such plates; and the flat surfaces of the under sides of all of these plates are all in the same horizontal plane, which, as most clearly represented in Fig. 5, is coincident with the level assumed by the bottom surface of a box when fed to and retained within the box carrier, and also with the upper peripheral surface of the gum rolls G G which run in the gum boxes G², in diametric opposition as regards the center of the dial like support B. The gum supplying means including the gum box and gum rolls are of ordinary kind; and the gum rolls, as common, are continually rotated by the belts G³ driven from any suitable source of power and running around the pulleys G⁴ on the gum roll shafts.

The intermittent revolute movement is imparted to the dial like support B by means as follows:—The said support B is made with a hub having at its lower portion a flange B² provided with a set of 6 rectan-

gularly spaced studs B³ with which coacts a pawl B⁴ carried by a slide B⁵ which is reciprocated by pitman rod B⁶ connected to said slide and eccentrically to a wheel B⁷ which is mounted on the countershaft H driven through the gears H² and H³ from the power shaft H⁴ on which the belt pulley H⁵ is shown. The wheel B⁷ also has a path cam J which actuates the plunger mechanism.

One-sixth way around from the location of each chute and box carrier thereunder, with its appurtenant bars F F and the gum roller, is a label pile support K, the diametrically opposite pair of these being fully shown in plan in Fig. 3, while only one thereof is visible in Fig. 2. Each label pile support consists of a comparatively long and narrow table having a depending stem K² vertically guided through the bed of the machine and relatively to which stem an elevating spring K³ is applied, as seen in Figs. 2 and 4, so that when the table is not restrained, by means to be hereinafter referred to, in its lowered position, it, with the pile of labels k thereon, will be spring pressed upwardly so that the uppermost label will be carried, by its intermediate portion, against the bottom of the box, while its end portions will be forced against the under faces of the gum receiving members F F. The little label tables K K have upstanding pins or rods k² for keeping the labels in place, while at the front is a spring frame k³ which may be forwardly swung to open the label receiving space for the easy insertion of fresh supplies of labels as they are needed. The means for retaining the label pile supports in their lowered position for the greater part of the time and for readily permitting them to rise is combined with the plunger mechanism which is appurtenant to the means for ejecting the boxes from the box carriers and which is co-operative with the box folding mechanism.

At the front and rear of the machine, and one-sixth way around from the locations of the label pile supports are the folding boxes L L, such relative locations being seen in Figs. 3 and 4; and one of these folding boxes is represented in sectional elevation in Fig. 8. These folding boxes are of substantially rectangular tubular form having their open tops or mouths slightly below the level of the bottoms of the gum receiving plates F F and the bottoms of the box carriers; and they are provided with opposite inwardly extending brushes f f having operative effect for the wrapping actions of the labels to U-form relatively to the boxes forced into the folding mechanism. Each label folding or wrapping mechanism, including the folding box or throat comprising portion L, also comprises "first" and "second" inturners, generally represented

by M and N, the first one of these inturners being actuated by the plunger mechanism, while the second one N is actuated by co-action therewith of the revolute dial B. The plunger mechanism comprises the aforementioned pair of vertical slideways a^2 , a^3 , in which the slides g are fitted for vertical movements, said slides being united by the cross bar h , to the centrally located hanger h^2 of which the cam operated lever O has connection, such lever being intermediately pivotally mounted at i while its end which is adjacent the aforementioned path cam j is provided with a friction roller z^2 having engagement in a usual manner in the cam groove. The aforementioned forward members E E are to all intents and purposes as one with the slides g , and they have depending plungers P, P, the same being in vertical alignment with the centers of the folding mechanisms, and also so positioned that in their descent they will enter and pass through an opposite pair of the box carriers for the expulsion of boxes therein from the latter down into the throats of the folding mechanisms. Each reciprocating slide g has at the lower end thereof a downwardly and outwardly inclined or cam shaped bar j , the opposite pair of these being shown in Fig. 1, while the front one is shown in Figs. 2 and 4; and each one of these cam shaped bars j coacts with an upstanding arm of a bell crank lever Q, the more or less nearly horizontal arm of which has engagement with the stud or shoulder m of the depending guiding and supporting rod K ^{2} of the label pile support K. Thus when the plunger mechanism is in its elevated position, the blank pile supports will be depressed, but when the plunger mechanism is lowered, the bell cranks Q are permitted to so swing as to leave the blank pile supports subject to the elevating actions of their springs K ^{3} to force them up against the bottoms of boxes in box carriers thereover and against the lower faces of the gum receiving members F F.

The "first" inturner M of each label wrapping or folding mechanism consists of a more or less nearly upright swinging lever pivoted at o , having at its upper end a finger plate p , and also provided at its upper portion with the roll o^2 against which impinges a cam like bar q carried by, and in depending relation to one of the slides of the plunger mechanism, this inturning device and its means for forcing it to its normal position outwardly just described, being duplicated at front and rear sides of the machine, while the means for forcing each of these inturners inwardly over and across the throat of the folding box, when the elevated position of the cam bar q permits, consists in the simple provision of a spiral spring p^2 . The motions are timed so that the first inturner

M will be moved inwardly over the throat of the folding mechanism and will then outwardly retreat before the second inturner N is operated:

Each duplicated "second" inturner N consists of an upstanding lever s pivoted at s^2 and having at its upper end a rigid or integrally formed wrist or crank-like extension s^3 carrying also a rigid angular extension s^4 provided at its extremity with a friction roll s^5 and a spring s^6 maintains this angular lever like element s , s^3 and s^4 in its outwardly swung position, that is to the rightward as viewed in Fig. 8. The inturning finger t of this second folding device is pivotally mounted on the crank-like or wrist portion s^3 and is downwardly drawn by the spring t^2 , its extremity always retaining bearing on the upper edge portion of the wall of the folding box L.

The edge portion of the dial is made with shoulders u , the same being produced by the simple expedient of forming recesses in the under surface of the marginal portion of the dial, these shoulders having, when they reach the roller provided extremity of the angular lever-like and swinging support for the inturning finger t , a dragging effect on such lever-like support for the proper inward operation of the inturner; and in this action as the dial B progresses or has its revolubly progressing movement, its shoulder u will pass from engagement over and away from the roller s^5 as permitted by the slight descent of such roller incidental to its movement in a slightly downward and inclined arc. When the shoulder u shall have freed itself from the roller s^5 , the spring s^6 will be effective to outwardly return the second inturner to its normal inactive position. In this machine there are 6 recesses forming six of the shoulders u , and the level lower edge portion of the dial B is continuous between one shoulder forming recess and another. Therefore, in practice the second inturner after having been inwardly moved remains inwardly during the short period of one step-like movement of the dial.

In the operation of the machine supplies of labels are provided on both of the little label tables or "elevators" K, and boxes filled, for instance, with cartridges or other contents, are provided into the chutes D D by being slid thereinto from the upper feed table R, as will be clearly understood on reference to Fig. 4. The machine being started, the box carriers C C will successively come to and pass under the delivery ends of the chutes receiving the box therefrom; the bottom of the box will be, as before stated, fully as low as the lower open end of the box carrier and will be brought onto, and subjected to the gum delivery action of, the gumming roll G. In the step by step revoluble movements of the dial, the

plates F F will in their impingement over the top of the gum roller, receive a surfacing of gum as well also as does the bottom of the box. In the next pass of a given box carrier with a box therein, the label pile support ascends to bring the uppermost label of the pile against the bottom of the box and against the gum surfaces of both of the gum receiving bars or members F F; and when shortly thereafter the gum pile support is forced downwardly to the lower level, the uppermost label of the pile is left adherent by its central portion on the bottom of the box and by its end portions on the under surface of the members F F. The box and its carrier and the label are next moved to position over the throat of the folding mechanism whereupon the plunger P descending, expels the box from the box carrier down into the folding box L between the opposed brushes f f, the forcible downward movement of the box causing a stripping of the label off from the label gumming members F F, and the label,—which may be of sufficient length to more than encircle the box,—is carried to an elongated U-shape with its extremities upstanding above the upper end of the box. The pressure of the brushes causes the label to adhere to the opposite sides of the box, it being appreciated that when the label is first moved against the back of the box by the pressure of the spring k, it becomes thereby firmly stuck to the box bottom. Concurrently with the upwardly retreating motion of the plunger, the first inturning device M becomes effective to fold the forwardly located extremity of the label which is upstanding above the top of the box, flatwise onto and across the box top, and then under the progressive movement of the dial like box carrier support B, the second label inturning device N becomes operative to fold the other or rearwardly located portion of the label which had been upstanding above the top of the box, flatwise onto and for adhesion against the already inturned forward extremity of the label. A box, for instance, delivered into the box carrier at the point 10, becoming gummed on its bottom as does also the under surface of the adjacent gum receiving members F F under one-sixth of a revolution comes over the label pile support, and it as well as said members F F receiving a label on their bottom, has the label wrapping operation completed in part while remaining over, and in part while passing around and away from the wrapping mechanism at the front of the machine; and while these operations are being performed between the point 10 and the front of the machine, identically the same operations are being performed between the point 12 and the rear side of the machine so that respective portions of the labeling operations are simultaneously per-

formed on two boxes and two entirely wrapped boxes are simultaneously downwardly moved in the substantially tubular folding boxes L. And while several of the boxes are in course downwardly through the folding box L, they are successively discharged from the bottom thereof, into any proper receptacle therefor by boxes incoming at the top. After a box carrier moves from under the lower delivery end of the chute D carrying with it the box taken thereby, the next lowermost box in the chute will fall to the level of the top of the revoluble box carrier support,—such top being constituted by the level surfaced bracket plates e, so that in operation and as a matter of fact, the boxes are not delivered into the box carriers C at the tops thereof, but are taken sidewise thereinto through the open fronts of the trough-like carriers until the backs of the carriers reach the backs of the boxes, whereupon the boxes will drop down into the carriers as far as permitted by the retaining fingers d; and in order that each box may not in any way be obstructed by the chute, the lower portion of the front of the chute, as represented in Fig. 6, is shortened, that is it terminates sufficiently high to form no obstacle to the box being swept as the box carrier passes under the chute 95 forwardly and out from under the chute.

It will be manifest that the utilization of this machine may be made for merely applying labels or stickers on the lower ends or sides of the boxes, for applying the labels so that they cover in whole or part of the width of the lower end of the box and one or more of the sides, or for applying labels to entirely encircle the box. The term "bottom" as herein employed in respect to the boxes is used relatively to the positions of the boxes as handled or carried in the machine; and in many cases the so termed bottom of the box is actually one of the box ends and not the box bottom as ordinarily considered. Where, for instance, cartridge boxes having covers partially telescoping over the sides of the boxes are run in the machine, the labels are effective for sealing the box and connecting the covers to the box bodies.

Changes of minor character may be made in the machine without departing from the present invention.

I claim:

1. In a labeling machine, in combination, a support and means for intermittently revolubly moving it, said support having a downwardly opening box-carrier, and a flat surfaced member, carried by said support, adjacent the box-carrier, a gumming mechanism, over which the box-carrier and said flat surfaced member have their course of movement, a vertically movable label support, over which the box-carrier and said

member also move, and means for periodically elevating the label support, relatively to the box-carrier and said member, a folding mechanism to a position over which the box-carrier moves, and means for forcing a box from the box-carrier and with it a label, to the action of the folding mechanism.

2. In a labeling machine, in combination, a revoluble box carrier having a gum receiving member adjacent thereto, and means for moving the carrier and said member in unison, a gum roll in contact with which said gum receiving member moves, a support for labels and means for moving same whereby a label thereon will become adherent on said gum receiving member, means for folding a label relatively to a box, and means for forcing a box from the box carrier and with it a label from adhesion on said gum receiving member to the action of the folding mechanism.

3. In a labeling machine, in combination, a box carrier having a box exposing and delivery opening at its bottom and means for yieldingly retaining a box therein, a gummer over which a box carrier is movable whereby the box receives therefrom a surfacing of gum on its bottom, a holder for a pile of labels, and means for moving it vertically whereby a label becomes adherent on the gum surfaced bottom of the box, means for imparting a progressive movement to the box carrier whereby it has positions successively over the gummer and the label holder and means for expelling the box from the box carrier.

4. In a labeling machine, in combination, a revoluble downwardly opening box-carrier, and horizontal members having flat bottom gum receiving surfaces, substantially at the level of the bottom of the carrier, and located adjacent, and in advance and to the rear of the latter as regards its line of travel, a gummer, and a vertically movable label support over which the carrier and said gum receiving members are successively moved, means for intermittently revolably moving the carrier and said members, and means for periodically moving the label support upwardly relatively to the carrier and said members.

5. In a labeling machine, in combination, a revoluble downwardly opening box-carrier and horizontal members having flat bottom gum receiving surfaces, substantially at the level of the bottom of the carrier, and in advance and to the rear of the latter, a gummer, and a vertically movable label support over which the carrier and said gum receiving members are successively moved, means for intermittently revolably moving the carrier and said members, means for periodically moving the label support upwardly relatively to the carrier and said members, and means for ejecting a box

downwardly out from the carrier thereby stripping the label from its adhesion on the gum receiving members.

6. In a labeling machine, in combination, a revoluble downwardly opening box-carrier and horizontal members having flat bottom gum receiving surfaces, substantially at the level of the bottom of the carrier and in advance and to the rear of the latter as regards its line of travel, a gummer, a vertically movable label support and a wrapping mechanism, all located at different points below the path of the box carrier and said members, and over which they are successively moved, and a plunger above the path of the carrier and vertically aligned relatively to the wrapping mechanism, means for intermittently revolably moving the carrier and said members, means for periodically moving the label support upwardly relatively to the carrier and said members, and means for periodically reciprocating the plunger.

7. In a labeling machine, in combination, a revoluble support and means for intermittently revolably moving it, having at its outer edge portion a regularly arranged series of downwardly opening box carriers and provided at opposite sides of each carrier with gum receiving members having flat faced bottoms, a pair of diametrically opposite gum boxes having gum rollers therein, having their upper peripheral portions coincident with the level of the bottoms of said gum receiving members, a pair of diametrically opposite label supports also below the box carriers and gum receiving members, and a pair of vertically reciprocating plungers aligned with the wrapping mechanisms and located above the level of the box carriers, means for periodically and concurrently elevating the label pile supports, and means for simultaneously reciprocating said plungers.

8. In a labeling machine, in combination, a revoluble support and means for intermittently revolably moving it, having marginally a regularly arranged series of downwardly opening box carriers, each having a spring pressed finger operative at the bottom of the carrier for retaining a box against falling therethrough, and said revoluble support being provided at opposite sides of each carrier with gum receiving members having flat faced bottoms, a pair of diametrically opposite gum supplying rollers for coaction with the bottoms of said gum receiving members, a pair of diametrically opposite vertically movable label pile supports beneath the level of the gum receiving members, a pair of diametrically opposite chutes above the revoluble support for gravitatively feeding boxes to be taken by opposite pairs of the box carriers, a pair of vertically reciprocating plungers aligned

- with the wrapping mechanisms and located above the level of the box carriers, means for periodically and concurrently elevating the label pile supports, and means for simultaneously reciprocating said plungers. 5
9. In a labeling machine, the combination of a revolubly movable box carrier and gum receiving members oppositely located relatively to the carrier, means for applying gum on the under surfaces of said members, a label pile support located below the level of the carrier and said members, means for vertically guiding said label support, a spring for exerting an elevating force to said support, a pivoted lever engaging the label support and operative to depress it, and a reciprocatory part having a member coacting with, and for controlling the movements of, said pivoted lever. 10
10. In a labeling machine, the combination of a revolubly movable box carrier and gum receiving members oppositely located relatively to the carrier, means for applying gum on the under surfaces of said members, a label pile support located below the level of the carrier and said members, having a depending guiding stem, provided with a transverse projection, a spring connected to said stem for exerting an elevating force thereto, a pivoted angular lever having an arm thereof in engagement with said transverse projection, and operative to depress it, a reciprocatory slide having a cam coacting with the other arm of said lever whereby the label pile support is alternately lowered, and permitted to ascend under the action of its elevating spring. 15
11. In a machine of the character described, the combination with a horizontal intermittently revoluble table-like support having, marginally thereof, a regularly spaced series of upwardly and downwardly opening box receiving carriers, each comprising opposite side and rear upstanding walls, but open at their forward sides, and each having a yielding box retaining member, of a chute above the revoluble support for gravitatively delivering boxes at its bottom in the path of the carriers, and a gum roll beneath the carrier support so positioned that boxes revolubly conveyed by the carriers will have, by their bottoms, wiping actions on said gum roll. 20
12. The combination with a horizontal intermittently revoluble table like support having, marginally thereof, a regularly spaced series of upwardly and downwardly opening box receiving carriers each comprising opposite sides and rear upstanding walls, but open at their forward sides, and each having an outwardly yielding box retaining member, and horizontal bars at front and rear of the carriers having gum receiving surfaces in a coincident plane which is adjacent the bottom of the carriers, of a 25
- chute above the revoluble support for gravitatively delivering boxes at its bottom in the path of the carriers, and a gum roll beneath the carrier support so positioned that boxes revolubly moved in the carriers and the lower surfaces of said bars will have wiping and gum receiving coaction with said gum roll. 30
13. In a labeling machine, in combination, a revoluble downwardly opening box carrier having a gum receiving member adjacent thereto, and means for moving the carrier and said member in unison, a gum roll in contact with which said gum receiving member moves, a support for labels and means for moving same whereby a label thereon will become adherent on said gum receiving member, a vertically passaged folding box, over which the box carrier is periodically brought, a reciprocatory plunger for the expulsion of a box downwardly out from the carrier and for therewith stripping a label from the gum receiving member, forcing said box and label into the folding box, and a label inturner for folding an upstanding part of the label onto the top of the box. 35
14. In a labeling machine, in combination, a revoluble downwardly opening box carrier having gum receiving members at opposite sides of and adjacent the lower portion of the box carrier and means for moving the carrier and said members in unison, a gum roll in contact with which said gum receiving members move, a support for labels and means for moving same upwardly relatively to the box carrier and said gum receiving members, a vertically passaged folding box beneath the path of the box carrier, a reciprocatory plunger above the box carrier, vertically aligned with the folding box and a pair of label inturners located adjacent and movable over the top of the folding box, and means for successively operating them. 40
15. In a labeling machine, in combination, a box carrier having a box exposing and delivery opening at its bottom, means for yieldingly retaining a box therein, and gum receiving members adjacent and at opposite sides of the box carrier and near the level of the bottom thereof, a gum roll in contact with which said gum receiving members move, a support for labels and means for periodically upwardly moving same relatively to said box carrier and said gum receiving members, a vertically passaged folding box having oppositely located label inturners each consisting of a pivotally mounted swinging carrier and an inwardly projecting folding finger, a reciprocatory plunger for the expulsion of a box downwardly from the carrier, and with it a label into the folding box, and a member movable in unison with the plunger for operating one of the label inturners in one direction upon 45

- the descent of the plunger, and a spring for reversely moving such inturner, and means for imparting reciprocatory movement to the other inturner.
- 5 16. In a labeling machine, in combination, a box carrier having a box exposing and delivery opening at its bottom, means for yieldingly retaining a box in the carrier, and gum receiving members adjacent and at opposite sides of the box carrier having their under surfaces near the level of the bottom of the carrier, and a revoluble table like support on which the box carrier and said gum receiving members are mounted, a gum roll 10 in contact with which said gum receiving member is moved, a support for labels and means for periodically upwardly moving same relatively to said box carrier and said gum receiving members, a vertically passed folding box having oppositely located label inturners, each consisting of a pivotally mounted swinging carrier and a finger projecting inwardly toward the mouth of the folding box, a reciprocatory 15 plunger for the expulsion of a box downwardly from the carrier into the folding box, means for periodically swinging one of the inturners, and shoulders on the revoluble box carrier support for temporarily engaging and swinging the other inturner crosswise over the mouth of the folding box.
- 20 17. In a labeling machine, in combination, a support, and means for imparting a traveling movement thereto, means on said support for receiving and holding a box with its bottom exposed, gum receiving members, carried by said support, one in advance, and the other to the rear, of the box receiver, and having their under surfaces in the same 25 plane, means for applying a surfacing of gum on the bottoms of said members, a vertically movable label pile support, beneath the traveling support and having its location in the line of travel of said gum receiving members 30 beyond the gum applying means, means for imparting elevating movements to the blank pile support so that a label thereon becomes adherent on the gum receiving members, means for forcing a box out from its receiver, therewith stripping the label from said gum receiving members, means for folding portions of the label upon the sides of the box, and means for inturning the extremities of the label on the upper end of the box.
- 35 Signed by me at Springfield, Mass., in presence of two subscribing witnesses.
